CARTON

Robert Van Rosen, New York, N. Y., assignor to
 J. Makowsky Corporation, a corporation of New
 York

Application October 8, 1943, Serial No. 505,511

8 Claims. (Cl. 229—16)

The invention relates to cartons used as receptacles for various goods. Preferably, the carton will be made of some such material as cardboard or the like, which comes in sheet form. A blank will be cut from the sheet and then bent and folded into proper form to make the carton or receptacle.

The invention contemplates a neat-looking, relatively sturdy carton which may be especially useful as a container for jars and the like of cosmetics, although it may be used for any material.

In the accompanying drawings showing a specific form of the invention, Figure 1 is a plan view of a blank from which the carton may be made. Fig. 2 is a perspective view of the completed carton with the cover partly opened. Fig. 3 is a transverse vertical section taken from side to side with the cover closed. Fig. 4 is a transverse vertical section taken from front to back of the completed carton with the cover partly opened. Figs. 2, 3 and 4 are on scales larger than Fig. 1.

In Fig. 1 the blank from which the carton is to be formed is shown as a single sheet of cardboard or other material. The solid lines of the drawings show lines on which cuts are made. The dot-and-dash lines show lines on which folds are made and these may be scored or otherwise prepared for easy and accurate folding.

In forming the carton, the section 10 will form the main outside front wall of the carton. The section 11 is folded inwardly at right angles to the section 10 to form a front top wall. The section 12 is folded downwardly at right angles to the section 11 to form an inner front wall. Section 13 is folded outwardly at right angles to the section 12 to form a brace for the wall 12. The section 14 forms the outer left wall of the carton. The section 15 is folded inwardly at right angles to the section 14 to form the upper side wall. The section 16 is folded downwardly at right angles to the section 15 to form the inner side wall. The section 17 is folded outwardly at right angles to the section 16 to form a brace for the side wall 16. The section 18 is folded inwardly at right angles to the section 14 to form a part of the inner bottom of the carton. The section 19 forms the outer right side wall of the carton. The section 20 is folded inwardly at right angles to the section 19 to form the top side wall. The section 21 is folded downwardly at right angles to the section 20 to form the inner side wall. Section 22 is folded outwardly at right angles to the section 21 to form a brace therefor. The section 23 is folded inwardly at right angles to the section 19 to cooperate with the section 18 to form a part of the inner bottom of the carton. The sections 14 and 19 are folded backwardly at right angles to the section 10 so that the bottom members 18 and 23 slightly overlap.

The section 24 is folded inwardly at right angles to the side wall 14. The section 25 is folded inwardly at right angles to the side wall 19, and the sections 24 and 25 are interlocked by means of the slots 26 and 27 carried by them. It will be noted that the slot 27 is on the lower edge of the member 24 while slot 26 is on the upper edge of member 25 so that they may interlock in a manner well known. The members 24 and 25 thus join to hold the side members in place and to form a back wall. This completes a rectangular form having the bottom formed of the sections 18 and 23. The section 28 is then bent rearwardly at right angles to the front wall 10 so as to form the bottom of the carton and underlie the inner bottom 18, 23. The section 29 is then turned upwardly at right angles to the bottom 28 to form an outer rear wall. The section 30 is to be folded forward at the edge of the section 29, but before this is done section 31 may be folded backward to come in contact with the member 30. The section 29 will lie against the back of the interlocked members 24 and 25 and the combined members 30 and 31 may then be turned downwardly so as to lie substantially parallel to the back wall 29, the section 30 lying in contact with the inner side of the joined members 24 and 25, the joint between the members 30 and 31 being at the bottom of the carton. The section 32 may then be folded forward at right angles to the section 31 to form the cover for the carton. The section 33 may then be folded downward at right angles to the cover 32 and its end may be locked by passing through the slot 34 provided in the front wall 10.

The inner side wall members 16 and 21 are shorter than the outer side wall members 14 and 19, so that when they are formed in the carton the edges of 16 and 21 will lie against the inner wall 12 which is separated by the width of the section 11 from the outer front wall 10. The inner ends of the top side wall sections 15 and 20 are beveled at 39 and 40 so that they may slightly overlie the ends of the top 11 of the front side wall, thus giving the appearance of beveled joints. The sections 30 and 31 are both shorter than the back wall 29, so that when they are folded in they may be placed between the inner side walls 16 and 21. The members 24 and 25 are recessed at 37 and 38 from their ends inwardly so that the members 30 and 31 may lie wholly below the side top members 15 and 20, and they are so proportioned that the cover 32 may not at its hinge project above the box as a whole.

The cover 32 is hinged to the member 31. When an article is in the carton of such size that it more or less snugly fits between its walls, the article itself may rest against the section 31 and hold it in position so that the cover 32 will be free to be opened without causing the carton to unfold. This condition may persist

when the article is removed from the carton, depending largely on the substance of which the carton is made or how well it retains the shape into which it is folded. However, in order to assure the holding of the members 30 and 31 in position so as to form a proper base for lifting or hinging the cover 32, members 34 and 35 at the rear of the inner side walls 16 and 21 may be provided. These may be bent inwardly from the walls 16 and 21 and engage the section 31 toward its ends so as to hold the section 31 more or less rigidly in place to allow manipulation of the cover 32.

The slot engagement of the member 33 may not be necessary. The slot 34 and the member 33 may be omitted or may be differently formed and the cover may be held in place by other suitable means, or gravity may be sufficient to hold it in position. The bracing members 13, 17 and 22 at the bottoms of the inner side walls may be desirable to keep the inner side walls sufficiently distant from the other side walls, but they are not essential and when desired they may be omitted. The sizes, proportions, and specific arrangements of the various parts are not essential to all phases of the invention, and various changes and omissions may be made without departing from the invention.

I claim as my invention:

1. In a carton formed from a single sheet of material, a front wall having a slot therein, side walls articulated at each end of the front wall, side top walls articulated at the tops of the side walls and extending inwardly and having their front ends inclined inwardly, inner side walls articulated at the inner sides of the top side walls and extending downwardly, side wall brace members articulated at the lower edges of the inner side walls and extending outwardly to the side walls, a front top wall articulated at the top of the front wall and extending inwardly and underlying the inclined ends of the top side walls, an inner front wall articulated at the inner edge of the front top wall and extending downwardly at the front ends of the inner side walls, a front wall brace member articulated at the bottom of the inner front wall and extending outwardly to the front wall, inner bottom members articulated at the bottom edges of the side members and extending inwardly in contact with the side wall and front wall brace members, connecting members articulated to the rear ends of the side walls and extending inwardly and interlocking with each other, a bottom member articulated at the bottom edge of the front wall and extending rearwardly to the rear ends of the side walls, a rear wall articulated at the rear edge of the bottom member and extending upwardly substantially in contact with the rear side of the connecting members, a first reinforcing member articulated at the top edge of the rear wall and extending downwardly substantially in contact with the inner side of the connecting members, a second reinforcing member articulated at the bottom edge of the first reinforcing member and extending upwardly substantially in contact therewith, both reinforcing members lying between the inner side walls, inwardly extending members near the rear ends of the inner side walls engaging and retaining the reinforcing members, a cover member articulated at the top edge of the second reinforcing member and extending forwardly, and a locking flap articulated to the front edge of the

cover member and extending downwardly and engaging the slot in the front member.

2. In a carton formed from a single sheet of material, a front wall having a slot therein, side walls articulated at each end of the front wall, side top walls articulated at the top of the side walls and extending inwardly and having their front ends inclined inwardly, inner side walls articulated at the inner sides of the top side walls and extending downwardly, side wall brace members articulated at the lower edges of the inner side walls and extending outwardly to the side walls, a front top wall articulated at the top of the front wall and extending inwardly and underlying the inclined ends of the top side walls, an inner front wall articulated at the inner edge of the front top wall and extending downwardly at the front ends of the inner side walls, a front wall brace member articulated at the bottom of the inner front wall and extending outwardly to the front wall, inner bottom members articulated at the bottom edges of the side members and extending inwardly in contact with the side wall and front wall brace members, connecting members articulated to the rear ends of the side walls and extending inwardly and interlocking with each other, a bottom member articulated at the bottom edge of the front wall and extending rearwardly to the rear ends of the side walls, a rear wall articulated at the rear edge of the bottom member and extending upwardly substantially in contact with the rear side of the connecting members, a first reinforcing member articulated at the top edge of the rear wall and extending downwardly substantially in contact with the inner side of the connecting members, a second reinforcing member articulated at the bottom edge of the first reinforcing member and extending upwardly substantially in contact therewith, both reinforcing members lying between the inner side walls, a cover member articulated at the top edge of the second reinforcing member and extending forwardly, and a locking flap articulated to the front edge of the cover member and extending downwardly and engaging the slot in the front member.

3. In a carton formed from a single sheet of material, a front wall, side walls articulated at each end of the front wall, side top walls articulated at the tops of the side walls and extending inwardly, inner side walls articulated at the inner sides of the top side walls and extending downwardly, side wall brace members articulated at the lower edges of the inner side walls and extending outwardly, a front top wall articulated at the top of the front wall and extending inwardly, an inner front wall articulated at the inner edge of the front top wall and extending downwardly, a front wall brace member articulated at the bottom of the inner front wall and extending outwardly, inner bottom members articulated at the bottom edges of the side members and extending inwardly, connecting members articulated to the rear ends of the side walls and extending inwardly and interlocking with each other, a bottom member articulated at the bottom edge of the front wall and extending rearwardly to the rear ends of the side walls, a rear wall articulated at the rear edge of the bottom member and extending upwardly substantially in contact with the rear side of the connecting members, a first reinforcing member articulated at the top edge of the rear wall and extending downwardly substantially in contact with the inner side of the connecting members, a second reinforcing member articulated at the bottom edge of the first reinforcing member and extending upwardly substantially in contact therewith, both reinforcing members lying between the inner side walls, a cover member articulated at the top edge of the second reinforcing member and extending forwardly, and a locking flap articulated to the front edge of the cover member and extending downwardly substantially in contact with the

inner side of the connecting members, a second reinforcing member articulated at the bottom edge of the first reinforcing member and extending upwardly substantially in contact therewith, both reinforcing members lying between the inner side walls, a cover member articulated at the top edge of the second reinforcing member and extending forwardly, and a locking flap articulated to the front edge of the cover member and extending downwardly.

4. In a carton formed from a single sheet of material, a front wall, side walls articulated at each end of the front wall, side top walls articulated at the tops of the side walls and extending inwardly, inner side walls articulated at the inner sides of the top side walls and extending downwardly, side wall brace members articulated at the lower edges of the inner side walls, a front top wall articulated at the top of the front wall, an inner front wall articulated at the inner edge of the front top wall and extending downwardly at the ends of the inner side walls, a front wall brace member articulated at the bottom of the inner front wall, connecting members articulated to the rear ends of the side walls and extending inwardly and interlocking with each other, a bottom member articulated at the bottom edge of the front wall and extending rearwardly to the rear end of the side walls, a rear wall articulated at the rear edge of the bottom member and extending upwardly substantially in contact with the rear side of the connecting members, a first reinforcing member articulated at the top edge of the rear wall and extending downwardly substantially in contact with the inner side of the connecting members, a second reinforcing member articulated at the bottom edge of the first reinforcing member and extending upwardly substantially in contact therewith, both reinforcing members lying between the inner side walls, and a cover member articulated at the top edge of the second reinforcing member and extending forwardly.

5. In a carton formed from a single sheet of material, a front wall, spaced inner and outer members forming side walls articulated at each end of the front wall, connecting members articulated to the rear ends of the side walls and extending inwardly and interlocking with each other, a bottom member articulated at the bottom edge of the front wall and extending rearwardly to the rear end of the side walls, inner bottom members articulated at the bottom edges of the side members and extending inwardly in contact with the bottom member, a rear wall articulated at the rear edge of the bottom member and extending upwardly substantially in contact with the rear side of the connecting members, a first reinforcing member articulated at the top edge of the rear wall and extending downwardly substantially in contact with the inner side of the connecting members, a second reinforcing member articulated at the bottom edge of the first reinforcing member and extending upwardly substantially in contact therewith, both reinforcing members lying between the inner side wall members, and a cover member articulated at the top edge of the second reinforcing member and extending forwardly.

6. In a carton formed from a single sheet of material, a front wall, spaced inner and outer members forming side walls articulated to the front wall, connecting members articulated to the rear edges of the side walls and interlocking with each other, a bottom member articulated at

the bottom edge of the front wall and extending rearwardly to the rear end of the side walls, a rear wall articulated at the rear edge of the bottom member and extending upwardly substantially in contact with the rear side of the connecting members, a first reinforcing member articulated at the top edge of the rear wall and extending downwardly substantially in contact with the inner side of the connecting members, a second reinforcing member articulated at the bottom edge of the first reinforcing member and extending upwardly substantially in contact therewith, both reinforcing members lying between the inner side wall members, and a cover member articulated at the top edge of the second reinforcing member.

7. In a carton formed from a single sheet of material, a front wall, spaced inner and outer members forming side walls articulated at each end of the front wall, connecting members articulated to the rear ends of the side walls and extending inwardly and interlocking with each other, a bottom member articulated at the bottom edge of the front wall and extending rearwardly to the rear end of the side walls, a rear wall articulated at the rear edge of the bottom member and extending upwardly substantially in contact with the rear side of the connecting members, a first reinforcing member articulated at the top edge of the rear wall and extending downwardly substantially in contact with the inner side of the connecting members, a second reinforcing member articulated at the bottom edge of the first reinforcing member and extending upwardly substantially in contact therewith, both reinforcing members lying between the inner side wall members, inwardly extending members near the rear ends of the inner side wall members engaging and retaining the reinforcing members, a cover member articulated at the top edge of the second reinforcing member and extending forwardly, and a locking flap articulated to the front edge of the cover member.

8. In a carton formed from a single sheet of material, a front wall, side walls articulated at each end of the front wall, side top walls articulated at the tops of the side walls and extending inwardly, inner side walls articulated at the inner sides of the top side walls and extending downwardly, a front top wall articulated at the top of the front wall, an inner front wall articulated at the inner edge of the front top wall and extending downwardly, connecting members articulated to the rear ends of the side walls and extending inwardly and interlocking with each other, a bottom member articulated at the bottom edge of the front wall and extending rearwardly to the rear ends of the side walls, a rear wall articulated at the rear edge of the bottom member and extending upwardly substantially in contact with the rear side of the connecting members, a first reinforcing member articulated at the top edge of the rear wall and extending downwardly substantially in contact with the inner side of the connecting members, a second reinforcing member articulated at the bottom edge of the first reinforcing member and extending upwardly substantially in contact therewith, both reinforcing members lying between the inner side walls, and a cover member articulated at the top edge of the second reinforcing member and extending forwardly.
